John T. Strong, Inventor
By his Attorney, Jonathan Dederer, New York.

UNITED STATES PATENT OFFICE.

JOHN N. STRONG, OF PHILADELPHIA, PENNSYLVANIA.

TEA OR OTHER CADDY.

SPECIFICATION forming part of Letters Patent No. 470,018, dated March 1, 1892.

Application filed June 18, 1891. Serial No. 396,688. (No model.)

To all whom it may concern:

Be it known that I, JOHN N. STRONG, a citizen of the United States, residing in the city and county of Philadelphia, State of Pennsylvania, have invented a new and useful Improvement in Tea or other Caddies, which improvement is fully set forth in the following specification and accompanying drawings.

My invention relates to improvements in tea or other caddies; and it consists of a caddy having a drawer with a chamber therein, which in one position is automatically supplied with a quantity of tea or other substance and in another position discharges the same, whereby a certain quantity of the contents of the storage-chamber of the caddy may be discharged therefrom by the operation of the said drawer without being exposed to the atmosphere during the measuring of the same.

It further consists of the combination of parts, as hereinafter set forth.

Figure 1 represents a perspective view of a caddy embodying my invention, the top being partly broken away. Figs. 2 and 3 represent vertical sectional views of the device at right angles, respectively, to each other. Fig. 4 represents a vertical section of a detail portion of the device. Fig. 5 represents a perspective view of a receiving or storage chamber of the caddy.

Similar letters of reference indicate corresponding parts in the several figures.

Referring to the drawings, A designates a casing or caddy in which are located side by side a number of receiving or storage chambers B, having the openings C in their tops for the admission of the tea or other substance held therein. The lower end walls D of the chamber are inwardly inclined, forming a spout with an opening at its lower end for the easy discharge or flow of the material therefrom, and the front of the chamber has a glass or other transparent window D', whereby the contents of the said chamber may be readily ascertained; a scale on the outer surface of the caddy indicating the amount therein. The said chambers B are seated on a partition-wall E, which has openings therein coinciding with the openings in the lower ends of the chambers B. Below the partition-wall E and moving on a partition-wall or support

F are the drawers G, each of which consists of a block or piece of suitable material adapted to close the bottom opening of the receiving-chamber, except when the hole or opening H registers therewith, when the said drawer is in its normal position, as in Fig. 3, so that the said opening H can be filled by the flow of the tea or other substance from the receiving-chamber, the bottom of the opening H then being closed by the wall F. Intermediate blocks P' are placed between the drawers, forming guides for the same. In the wall or support F are the openings J, each communicating with a spout K, leading outside of the caddy.

The openings H of a drawer are adapted to register with an opening J of the wall F when the said drawer is drawn out, or in the position shown in Fig. 4, which position is determined by means of a stop L, secured to a tail portion of the drawer and working in a slot M in the under side of the wall E, the said pin abutting against a shoulder N on the under side of said wall when the drawer is in proper place. A spring P, secured to the caddy and to the drawer, insures the return of the latter to its normal position when the hand of the operator releases the knob Q of the latter, by which it is drawn out.

It will be seen that the openings H may be of any size or depth, and as they register with the lower ends of the chamber B they receive the material therefrom when in line therewith without any spilling of the same. As the drawers are pulled outwardly the tea or other substance in the openings H' is drawn to the openings J, so that the said substance will be discharged through the spouts K without exposing the contents of the casing to the atmosphere.

The lid of the casing is provided with a catch, hasp, or staple or other means for securing or locking said lid.

Having thus described my invention, what I claim as new, and desire to secure by Letters Patent, is—

A caddy consisting of a casing, with a horizontal wall with openings therein, storage-chambers seated on said wall and having inclined lower walls fitted in said openings of the aforesaid horizontal wall, a support below said horizontal wall and open only at its for-

ward portion, from which a series of spouts depend to the exterior of the casing, drawers closely confined between said horizontal bottom and said support, having openings to align with either the openings in the storage-chambers or said supports and rearwardly extending extensions to close against the bottoms of said storage-chambers, springs connected to said drawers to return the same to

a normal position, stops to limit outward movement of said drawers, and grooved guides on each side of said drawers, all combined substantially as described.

JOHN N. STRONG.
